(54) **STAVES FOR TRUSS HOOPS**

(76) Inventor: **Amory Amaden**

Amory Amsdorff a citizen of the United States
Letters Patent.

The Schedule referred to in these Letters Patent and making part of the same, containing a description in the own words of the said Amory Amsdorff himself of his improvement in the Machine for making Coopers Staves ready for the Treen Hoop.

Fig: 1. The block carriage & saw A. The block saw runs in a perpendicular manner like that of an ordinary saw-mill, and faces the saw-mill saw directly back of the head block, so that when the block carriage receives the plank intended to be worked into staves, the block saw cuts it smoothly (the plank standing upright and on its edge) and the saw sticks and cuts it off near the letter B. B. the block carriage has four motions: 1st, by being moved by the swivel dogs C. C. it plays towards the block saw where the stick, placed upon it is bitten; then by springs placed under the carriage B. (which cannot be represented in the drawing) as soon as the notch gauges 1. 2. 3. 4 & 5 attached to the main saw-mill carriage D. have passed the swivel dogs C. C. then the springs 1. 2. 3 & 4 (which are sprung by the first operation) instantly throw the block carriage B. to its first position; being now out of gear & detached from the saw-mill carriage D. the weight E suspended by the rope F, draws the block carriage until the end of the plank strikes the block gauge G. which measures it the proper length for a stave; the block saw is all the time running and is ready to cut whenever the notch gauges begin to take effect on the swivel dogs at which time the block carriage begins to move towards the saw; it then begins to cut & continues precisely the same operation until the plank

is worked up which will be in the same length of time that the saw-mill carriage runs through. when the carriage D returns, having its arm E extended, it takes the block B. by the hand J. and leads it back to the place from whence they both started, at which time the carriage B is ready to receive a part of D's load or the plank just as sawed. - If the keeper or key retains the carriage B. after the plank has moved by the gauge G, until the plank is sawed in two parts. - I. - the sloping dog that holds the plank while sawing. - II. the lower pulley. the upper pulleys through which the rope F runs. O. the stable to which the rope is attached. P P. the long sills for the carriage B. - a. the spikes which keep the plank from slipping. - b. b. the short cross sills. - C. the perpendicular arms or half shafts that keep the plank erect on its edge. d. d. govern the gauge G for the desired length of the stave. -

Fig 2. A cylinder saw for sawing staves of any size. - A the cylinder is composed of cast iron & may be of any size according to the size of the stave wanted; for instance, for barrel staves it will require about 9 feet from the back end to the muzzle & about 29 inches in diameter. B the bridge end, extends from 10 to 12 inches in length exceeding 3 or 4 inches beyond the back end into the inside of the cylinder & into which the shaft runs & serves for the gauge or near it the saw - two as well as one of these may be hung on the same shaft by turning the teeth the other way, having in that way two sets of teeth opposite each other.

C. the saw plate will be from 9 to 10 inches wide & is placed on from 1 to 1 1/2 on to the saw. D. the feeder is an iron or steel screw about about $\frac{7}{8}$ ths of an inch in diameter with a flat pinning in every successive revolution about one fourth an inch which runs into the shaft & extends to the back end of the carriage.

Fig 3. In case of 2 cylinders on the same shaft, one of the screws must

must be one left handed & opposite the other. E. points west for the feeder.

Fig 3. The cylindrical carriage. A the open dye which passes over the screw-feeder, being when joined together, a jumbo screw so-called; B. C. D. cog-wheels for loosening or tightening the blocks. E. F. G. iron rods passing from one end of the carriage to the other throwing back or drawing up the iron arches that hold the spikes or dogs pins. E. is being left handed in their revolutions in consequence of C. being turned by a crank right handed and its ergs pushing into C. H. I. J. iron bolts to support the ends of the arches. K. L. M. N. O. P. conductors to direct the balls to the feeder, or centre of the cylinder; in this manner any number of slaves from 1 to 13. may be sawed at once. - Q. spring that holds the dye. - R. jibbed points that throw the carriage into gear & close the top parts of the dye, - this is done by the passing of the iron conductors into this fork & they are crowded together as they approach the side of the iron that holds the dye; it then passes along the screw, the dye being so small before mentioned threaded out as a screw. - S. guard that throws the carriage out of gear. T a spring that is constantly crowding the bars outward and the lower ends of the bars leave the fork described, this spring gradually opens the split dye so that it may move back over the screw without taking the threads. - U. V. W. arch pieces of cast iron or wrought iron which the dogs pins that hold the balls.

1. 2. 3. 4. 5. 6. The dogs. V The front & W the rear gauges for the thickness of the slaves. X. Y. arms that support the apron. Z. - The apron that receives the slaves and carries them out of the cylinder & drops them under the cylinder.

Fig 4. for listing slaves (so termed) or sawing joints & making each slave of an exact & uniform edge.

A. the perpendicular wheel saw. - B. the horizontal saw wheel. C. the centre bar on which the carriage runs. D. the carriage. E.

E. The rack whereon the staves from 1 to 6 or more are placed at a time; one edge is then applied to the perpendicular saw and carried thro' the length of the stave the frame turns easily and is then brought down to the horizontal saw, so that the other edge of the lot of staves are caued precisely like the first edge. - F. the follower which presses on the staves by the hand & hold them steady.

G. A bold fast with teeth to retain the follower wherever wanted after being pressed down.

H-H. frame for the circular saws. J-J. screws to direct the centre bar.

Fig. 5. - A. Case and director for the jointer. -

B. The stock which plays back & forward by a pitman.

C. The pitman. - Figs. 1.2.3.4.5.6.7.8. The jointer irons.

These are placed, 4 facing one way & 4 the other so that as the jointer moves back & forth, the staves move from the centre first toward one end and then toward the other & all the staves are placed as desired.

D. D. Gauge screws for the length of the staves.

E.E. The gauges where notches are cut to direct the stave and give it a bevel edge.

It must be understood that this machine is moved by water power & the one now in operation by the inventor is attached by principles familiar to every mechanic to a common saw mill.

Water power would do equally well for the preparation of staves after the plank for the purpose is properly sawed.
